[57] CLAIM

The ornamental design for a portable fluorescent light with magnetic support, as shown and described.

DESCRIPTION

FIG. 1 is a front perspective view of a portable fluorescent light with magnetic support showing our new design;

FIG. 2 is a front elevational view thereof;

FIG. 3 is a left side elevational view thereof;

FIG. 4 is a rear elevational view thereof;

FIG. 5 is a top view thereof;

FIG. 6 is a right side elevational view thereof; and,

FIG. 7 is a bottom view thereof.

The broken line showing of an electrical cord in FIGS. 1, 3 and 6 and a ballast in FIG. 1 is for illustrative purposes only and forms no part of the claimed design.

FIG. 6

FIG. 5

FIG. 7
